[57] CLAIM

The ornamental design for a garment hanger body, as shown and described.

DESCRIPTION

FIG. 1 is a perspective view of a garment hanger body showing my new design, the clamps being shown in the open condition;

FIG. 2 is a front elevational view thereof, a hook being shown in phantom;

FIG. 3 is a top plan view thereof;

FIG. 4 is a right side elevational view thereof with the hook shown in phantom, the left side being a mirror image thereof;

FIG. 5 is a rear elevational view thereof with the hook being shown in phantom;

FIG. 6 is a bottom plan view thereof; and,

FIG. 7 is a perspective view thereof, the clamps being shown in the closed condition.

The hook which is shown in phantom in FIGS. 2, 4 and 5 is for illustrative purposes only and forms no part of the claimed design.
